Inventor:

S. L. Wiegand

United States Patent Office.

S. LLOYD WIEGAND, OF PHILADELPHIA, PENNSYLVANIA.

Letters Patent No. 96,067, dated October 19, 1869.

IMPROVEMENT IN STEAM-GENERATOR.

The Schedule referred to in these Letters Patent and making part of the same.

To all whom it may concern:

Be it known that I, S. LLOYD WIEGAND, of the city and county of Philadelphia, have invented certain additional new and useful Improvements in the Steam-Generators for which Letters Patent numbered 67,621, and issued August 6, A. D. 1867, were granted to me by the United States of America.

The nature of my invention consists in an improved form of tank, so arranged as to have greater steam and water capacity, and to be more convenient of access for inspection, cleaning, and repairs.

A provision is also made in this invention for a more free intercommunication between the several tanks of which the generator is composed, so as to facilitate cleaning by "blowing off," and a more uniform water-supply in all the tanks. At the same time, the cost of production and labor of erection are materially diminished by this invention.

In addition to the above advantages, this invention embraces an improved mode of distributing the draught of the furnace, so as to heat the steam-generator more equally in all its parts, thus obtaining greater steam-generating capacity, with a diminished fuel consumption.

The precise nature of my invention will more fully appear in the following specification, and drawings thereto annexed, which I do hereby declare to be a full, clear, and exact description and representation thereof.

The same letters of reference apply to the same parts in the several figures.

Figure 1 is a sectional elevation.

Figure 2 is a front elevation.

Figure 3 shows a vertical section of the feed-pipe, and the end of a tank as connected thereto.

Figure 4 shows a plan of the parts embraced in fig. 3.

Figures 5 and 6, respectively, show a vertical section and a plan of the caps applied to the lower ends of the tubes, and the supports for the internal tubes.

A represents the steam-drum, connected with which, by means of the pipes U, inserted near the centres of their tops, are several tanks, marked B. The tops of the tanks B are convex.

From the bottoms of the tanks B hang the tubes C, containing the internal or circulating tubes D, which pass through the perforated plate F in the tank B.

The ends of the tanks B are not made, as heretofore, perpendicular, but are inclined, so as to afford easier access to the interior when the hand-hole plates V are removed; and when several beds of generators are built close together, the screw-bolts and nuts for securing the hand-hole plates V are more easily accessible.

The lower ends of the tubes C are closed by the

caps I, in which caps I are placed frames K, to support the inside or circulating tubes D.

The frames, or supports K are made either of wire or sheet-metal, although castings have been used for this purpose with satisfaction. Their function is to hold up the internal tube D concentric with the tubes C, and permit a free flow of water from the tubes D into the caps I.

Upon one end of each tank B there is formed a nozzle, W, which fits into an aperture, X, in the feed-pipe F, to which pipe F the several tanks are secured by screw-bolts G, with nuts and heads fitting in the pockets H in the feed-pipe F.

The tanks B, thus arranged and connected, have a free and direct communication with each other through the pipe F and the tubes U and drum A. A uniform level of water is maintained in them when in use, and they are rapidly emptied in "blowing off" through the pipe F.

The tanks B should be made of such dimensions as not to crowd each other when heated and the pipe F is cold. In this way, any strain on the joints, between the pipe F and the nozzles W of the tanks B, from expansion and contraction, is avoided, the elasticity of the tubes U relieving any differences between the expansion of the steam-drum A and the tanks B.

The furnace O is made directly under the caps I of the generator, and is fed by the door R, and the fuel supplied with air from the ash-pit Q, between the grates P.

Air may be heated and admitted above the grate in the same manner as in gas-consuming stoves and furnaces now in general use.

The gaseous products of combustion pass to the chimney through the flues L and S, in the wall M. They do not, however, pass in a large volume, but are divided by passing through the perforations N, in the upper portion of the wall M.

The practice pursued in the erection and use of this invention has been to make several rows of perforations, those being largest and most numerous at the top, and whenever the draught was found to be excessive, to reduce it by plugging up the perforations, beginning with those lowest down, until a satisfactory adjustment of the draught was obtained.

In some cases, the front wall, over the door, was made to project inward, as at T, in fig. 1, thus forming a chamber, Y, which I believe to be useful in supplying heat to the upper portions of the front tubes.

In all other respects but those hereinbefore described, this steam-generator and furnace are similar to the one described and patented in patent numbered 67,621, issued August 6, A. D. 1867.

What I claim as my invention, and desire to secure as such by Letters Patent, is—

1. The tank B, constructed as shown and described

2. The feed-pipe F, when combined and connected with the tanks, substantially as shown and described.

3. The separate supporting-pieces K, for the circulating tubes, in combination with the caps, as shown and described.

4. The chamber Y, with the deflector T, arranged substantially as shown and described.

In testimony whereof, I have signed this specification, and the drawings therein referred to, in the presence of two subscribing witnesses.

S. LLOYD WIEGAND.
